TELEPHONE REST

John J. Spissell, New York, N. Y.

Application July 1, 1937, Serial No. 151,523

4 Claims. (Cl. 248—121)

This invention relates to a telephone rest and it aims to provide a novel structure having incorporated therewith, various additional associated utilities and combinations.

5 A particular object is to provide such a construction wherein a telephone set, particularly of the French phone type, includes means for holding the combined receiver and transmitter, as such combined receiver and transmitter has to be 10 left, while seeking the party called.

Another object is to provide a structure having a calendar, picture or the like device, normally in operative position, and adapted to be displaced by the combined receiver and transmitter, in 15 order to support the same and hold it against accidental displacement.

The more specific objects and advantages will become apparent from a consideration of the description following taken in connection with accompanying drawings illustrating an operative 20 embodiment.

In said drawings—

Figure 1 is a view in side elevation of the improved combination telephone rest;

25 Figure 2 is a view of the device in substantially central vertical section;

Figure 3 is a detail section taken on the line 3—3 of Figure 1;

Figure 4 is a detail section taken on the line 30 4—4 of Figure 2;

Figure 5 is a detail section taken on the line 5—5 of Figure 2; and

Figure 6 is a fragmentary section taken on the same plane as Figure 2 but showing the draw 35 extended.

Figure 7 is a fragmentary view showing the hinged connection between the bracket and the article holder.

Referring specifically to the drawings wherein 40 like reference characters designate like or similar parts, 10 designates a base of any desired size or material, equipped with feet 11, if desired. A vertically disposed bracket or gooseneck 12 is detachably fastened in a socket member 13, integral 45 with the base, as by means of a screw 14.

The free end of said bracket or gooseneck 12 terminates over the base one side of center and attached thereto is a holder generally designated 15. Specifically, said holder consists of a panel 16 for instance of flexible metal whose ends are curled over to form clasps 17 adapted to secure calendar sheets, a picture or the equivalent as at 18, releasably against the panel, the free edges of the clasps 17 engaging such sheets 18.

50 Disposed in the tubular clasps 17 are rods 19

which may be of wood or any other suitable material and which have balls or enlargements 20 at each end, such balls being of greater diameter than the diameter of the clasps 17. It will be noted that a plurality of lugs 21 are provided on 5 the panel 16 into which the sheets 18 or the backing thereof may extend for more secure mounting.

Pivotaly connected or hinged together as at 22 to the panel 16, are attaching leaves 23 and 10 24, the former preferably including a flexible clamp 25 adapted to surround the free end of the gooseneck 12 and be secured thereto by a bolt or the equivalent 26, while the leaf 24 is secured to the end of such gooseneck or bracket 12 as by 15 means of a screw 27. The hinge means 22 includes a spring 28, so mounted as to maintain and urge the panel 16 to a substantially upright or perpendicular position.

In the use of the device, the lower or base section of a French phone is adapted to be detachably supported on or secured to the aforesaid base 10 and the socket device 13 as at 29 is shaped to correspond thereto or fit the same. When answering the phone, and it is necessary to leave 25 the same while seeking the party called or otherwise, the combined transmitter and receiver of the phone is placed against the holder 15, and the latter depressed to the horizontal or dotted line position shown in Figures 1 and 2, in which 30 position it remains due to its weight, being efficiently supported with the combined receiver and transmitter extending transversely of the clasps 17, and being prevented from accidental disengagement from the holder because the balls or 35 enlargements 20 extend above the clasps 17. When someone thereafter lifts the combined receiver and transmitter from the holder 15, the latter will return to vertical or upright position through the urgency of the said spring 28.

40 It will be noted that the base 10 is hollow to provide a space accommodating a suitable drawer as at 30, for a telephone book, notes, pad or the like. Obviously the drawer may be of any suitable construction and have any desired attachments 45 or accessories. The closed position is well shown in Figure 2 while the open position is suggested in Figure 6.

On the top of the base 10 a pencil holder is provided as at 32, one part 33 of which may serve as 50 a book stand or rest, the book being in an inclined position with the upper portion resting against the holder 15.

The structure is preferably illuminated, preferably having an ornamental electric lamp struc- 55

ture as at 34, being suspended by a U-shape bracket or support 35 preferably detachably connected as at 36 to a supporting plug 37, pivotally fastened as at 38 to the bracket 12. Electric wires 5 39, from any suitable source of supply extend to a socket member 40, carried by the support 37, and detachably engaged by the support 35, the conductors also extending through the latter and to the lamp device 34.

10 Various changes may be resorted to provided they fall within the spirit and scope of the invention.

I claim as my invention:

15 1. A structure of the class described having a base, said base being adapted to support a telephone or the like, a bracket rising from the base, an article holder supported by the bracket over the base, means urging said holder to a projected position, said holder being displaceable under the weight of a part of the telephone stand, said holder having means functioning in the latter position to prevent accidental detachment of such part.

20 2. A structure of the class described having a base adapted to support a telephone or the like, a bracket rising from the base, an article holder supported by the bracket and disposed over the base, means urging said holder to a projected

position, said holder being displaceable under the weight of a part of the telephone, said holder having curled ends forming clasps to secure an article against the holder, rods extending into the clasps, and enlargements on the rods functioning to prevent accidental detachment of said part. 5

3. A structure of the class described having an article holder, means urging said holder to a projected position, said holder being displaceable under the weight of a part of a telephone, said holder having curled ends forming clasps to secure an article against the holder, rods extending into the clasps, and enlargements on the rods functioning to prevent accidental detachment of said part. 10

4. A structure of the class described having a base adapted to support a telephone or the like, a bracket on the base, an article holder supported by the bracket, a leaf on the bracket to which the holder is pivoted, spring means engaging the holder and leaf urging the holder to a projected position, said holder being displaceable under the weight of a part of the telephone, said holder having curled ends forming clasps to secure an article against the holder, rods extending into the 20 25 clasps, and enlargements on the rods functioning to prevent accidental detachment of said part.

JOHN J. SPISSELL.
